(57) **CLAIM**

The ornamental design for a portable clothes drying rack, as shown and described.

DESCRIPTION

FIG. 1 is a front perspective view of a portable clothes drying rack, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view showing the portable clothes drying rack in a partially folded state;

FIG. 10 is a front view showing the portable clothes drying rack in a folded state;

FIG. 11 is an enlarged detail view of area 11 in FIG. 1;

FIG. 12 is an enlarged detail view of area 12 in FIG. 5;

FIG. 13 is an enlarged detail view of area 13 in FIG. 5; and,

FIG. 14 is an enlarged detail view of area 14 in FIG. 9.

The broken lines in the drawings illustrate the portions of the portable clothes drying rack, which form no part of the claimed design.

The dash-dot-dash broken lines encircling the enlarged views are for annotative purposes only and form no part of the claim thereof.

1 Claim, 14 Drawing Sheets
